(57) **CLAIM**

The ornamental design for a faucet with pull-out spout, as shown and described.

DESCRIPTION

FIG. 1 is a perspective view of our new design for a faucet with pull-out spout;

FIG. 2 is a rear elevational view of our new design for the faucet with pull-out spout;

FIG. 3 is a front elevational view of our new design for the faucet with pull-out spout;

FIG. 4 is a bottom plan view of our new design for the faucet with pull-out spout;

FIG. 5 is a top plan view of our new design for the faucet with pull-out spout;

FIG. 6 is a left side elevational view of our new design for the faucet with pull-out spout viewed from the side opposite the handle socket; and,

FIG. 7 is a right side elevational view of our new design for the faucet with pull-out spout viewed from the handle socket side.

The handle for the faucet with pull-out spout is not shown in any of the drawings and forms no part of the claimed design.
